UNITED STATES PATENT OFFICE.

GUSTAVOS HEIDEL, OF ST. LOUIS, MISSOURI.

CAR-BRAKE.

SPECIFICATION forming part of Letters Patent No. 275,650, dated April 10, 1883.

Application filed January 25, 1883. (No model.)

To all whom it may concern:

Be it known that I, GUSTAVOS HEIDEL, of the city of St. Louis, in the State of Missouri, have invented a certain new and useful Improvement in Street-Car Brakes, of which the following is a full, clear, and exact description, reference being had to the accompanying drawings, forming part of this specification, and in which—

10 Figure 1 is a bottom view of a car, showing my improvement applied. Fig. 2 is part in elevation and part in longitudinal section of the lower part of a car. Figs. 3, 4, 5, 6, 7, and 8 are enlarged views of different parts of 15 the brake. Figs. 9 and 10 illustrate how the brake can be used when the brake-shoes are located on the inside of the wheels.

20 My invention relates to street-car brakes intended to be operated by foot-power; and my invention consists in certain features of 25 novelty hereinafter fully described, and pointed out in the claims.

Referring to the drawings, A represents the body of a street-car; B, the axles; C, the 25 wheels, and D the brake-beams, with shoes D', as usual. The beams are connected by means of rods E to the lower ends of links F, depending from a hanger or bracket, G, secured to the bottom of the car, to which they 30 are pivoted by pins G'. To the lower ends of the links are pivoted short arms H, whose ends are secured together, and to the inner arms, I', of a double U-shaped frame, I, by a pin or pintle, J. The frame I, when secured in place, 35 is inverted, and between its inner arms, I', and outer arms, I², fit the inner and free ends of levers K, (see Figs. 3 and 6,) which are pivoted to the bottom of the car by fulcrum-brackets L, and whose outer ends extend to 40 the ends of the car, respectively, (see Figs. 1 and 2,) where they have pivoted to them arms M, that extend up through openings in the bottom of the car, and have secured to their upper ends foot-pieces N. It will now be seen

45 that when the outer end of either one of the levers K is forced downward, and its inner end thus raised, the frame I will be raised, drawing the lower ends of the arms or links F, and consequently the pull-rods E, toward 50 each other, (see Fig. 4, their natural position being shown in Fig. 5,) thus applying the brakes. When one lever is operated it has

no effect on the other, as will be plainly observed. When the outer ends of the levers are released they are thrown up by springs O, 55 secured to the bottom of the car. When the levers are pressed down they may be held in that position by catches M', on the outer faces of the arms M engaging with teeth of bars P, secured to the ends of the car. (See Figs. 60 2, 7, and 8.) The foot-pieces N are pivoted to the arms or blocks M, and are capable of being thrown into a vertical position, (see Fig. 8,) the object being this, that when the team is changed from one end of a car to the other 65 the driver first throws the foot-piece of this end of the car up into this vertical position, so that any one standing on the platform cannot accidentally or intentionally apply the brakes by stepping on the foot-piece, nor can 70 they by stepping on the upper end of the arm, for the lower end of the foot-piece—that is to say, the outer end of the foot-piece when it is in its natural position—will come against the bottom of the car, preventing the arm from 75 being pressed down far enough to apply the brakes.

If the brake-beams were on the inside of the wheels they would of course have to be forced apart, instead of being pulled together, 80 to apply the brakes, and my brake can thus be used as shown in Figs. 9 and 10, Fig. 9 showing the natural position of the parts, and Fig. 10 the position when the brakes are applied.

I claim as my invention—

1. In a car-brake, the combination of hanger G, links F, pivoted to the hanger, arms H, pivoted to the links, frame I, to which the links are pivoted, and lever or levers K, pivoted to 90 the bottom of the car, engaging with the frame I, and provided with a suitable foot-piece, all substantially as shown and described, the links F being connected to the brake-beams by suitable means, as set forth.

2. In a car-brake, the combination of hanger G, secured to the bottom of the car, links F, pivoted to the hanger, arms H, pivoted to the links, frame I, to which the links are pivoted, and levers K, pivoted to the bottom of the car, 100 engaging with the frame I, and provided with arms M and foot-pieces N, all substantially as shown and described, the links F being connected to the brake-beams, as set forth.

3. In a car-brake, the foot-pieces N, pivoted to the arms M of the levers K in such a manner that they can be turned up vertically, for the purpose set forth.

4. In a car-brake, the combination of a lever pivoted to the bottom of the car, having a foot-piece at its free end, a frame operated by the lever, a suitable hanger or bracket secured to the bottom of the car, links depending from

the hanger or bracket, arms connecting the frame to the lower ends of the links, and brake-beams connected with the lower ends of the links, as set forth.

GUSTAVOS HEIDEL.
